UNITED STATES PATENT OFFICE.

LOUIS LEONARD LUCE AND LEROY MATTSON, OF PORTLAND, OREGON.

INTERNAL-COMBUSTION ENGINE.

Application filed October 1, 1921. Serial No. 504,546.

To all whom it may concern:

Be it known that we, LOUIS L. LUCE and LEROY MATTSON, citizens of the United States, residing at Portland, in the county 5 of Multnomah, State of Oregon, have invented a new and useful Internal-Combustion Engine, of which the following is a specification.

This invention relates to an internal combustion engine and is designed more especially as an improvement upon the structure shown in Patent No. 1,390,572 issued to us on Sept. 13, 1921.

It is an object of this invention to reduce 10 the length of the patented motor as well as the pistons operating therein and to provide the upper portion of each cylinder with an integral wall projecting between the firing and the charging pistons so as to prevent 15 them from contacting with each other during the operation of the engine.

A still further object is to materially reduce friction by keeping the pistons out of contact with each other.

20 With the foregoing and other objects in view which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

25 In the accompanying drawings the preferred form of the invention has been shown.

In said drawings

Figure 1 is a vertical section through the engine.

30 Figure 2 is a section on line 2-2, Figure 1.

Figure 3 is a section on line 3-3, Figure 1.

Referring to the figures by characters 35 of reference 1 designates the casing of the engine, the same being provided with bearings 2 in which is journaled a shaft 3. An intermediate portion of the shaft is journaled in a bearing 4 carried 40 by a partition formed at the center of the casing, it being understood, as will be apparent by referring to Figure 2, that the casing 1 is made up of two substantially cylindrical portions formed integral with

each other as shown or suitably joined so 55 as to provide the partition 5 in which the bearing 4 is formed.

Extending upwardly from the casing are spaced cylinders 6 the diameters of which are considerably less than the diameters of 60 the cylindrical portions of the casing 1. These cylinders are formed integral with the casing and have their inner portions extending into the respective cylindrical portions of the casing as shown at 7, these 65 inwardly extending portions being eccentrically located within the cylindrical portions of the casing 1 as shown in Figure 2. They do not, however, contact with the walls of the casing. Those portions of the cylinders 70 projecting beyond the casing 1 are provided with a water jacket 8 and suitably mounted within each of the cylinders, preferably at the outer end thereof, is a spark plug 9.

The shaft 3 is provided with two pairs of 75 cranks indicated at 10 and 11. On the crank 10 is mounted a pitman 12 which is pivotally connected, as at 13, to a charging piston 14 having an eccentrically arranged opening 15 therein into which projects one of the 80 extensions 7. This opening is necessarily eccentrically disposed in order to receive the portion 7 which thus serves to guide the piston during its reciprocation within the casing 1. By constructing the charging 85 piston as described it becomes necessary to use but one pitman 12 for each charging piston. The space between the guide portion 7 and the wall of the casing 1 and within which the piston 14 works is closed 90 at its outer end except for a port 16 which opens into the cylinder 6 from which said guide portion 7 extends, the ports 16 of the two cylinders being disposed at opposite sides of the partition 5 as shown clearly in 95 Figure 1.

The crank 11 is engaged by a pitman 17 extending into and pivotally attached to a firing piston 18 adapted to work within the guide extension 7 and within the cylinder 6. 100 The head of this piston is provided at its periphery with a recess 19 adapted to register with the port 16 during the completion of each stroke of the piston away from its spark plug 9. This head is preferably 105 curved inwardly and laterally away from the recess portion 19 so that when said recess is registering with the port 16 the head has

moved past and has exposed an exhaust port 20 formed in the cylinder 6 diametrically opposite the port 16.

- A fuel intake port 21 opens into each 5 of the cylindrical portions of the casing 1, each port being in communication with the widest portion of the space between the guide portion 7 and the wall of the casing 1 and being located where it will only 10 be exposed or opened when the piston 14 reaches the limit of its suction stroke. It will be noted that each piston 14 has a crescent shaped recess or pocket 22 in its active face.
- 15 For the purpose of preventing leakage between the working parts suitable packing rings 23 can be extended around the pistons 14, the inner ends of the guide portions 7, and the end portions of each of 20 the pistons 18.

As a means for scavenging the engine there is provided between the cylinders 6 a pipe 24 having nozzles 25 extending therefrom for directing steam jets into the cylinder 6 directly above and close to the ports 16.

During the operation of the engine each piston 14 moves downwardly so as to uncover its intake port 21 and the partial 30 vacuum produced by this action will result in fuel rushing into the path of the piston so that on the return stroke of said piston it will compress the charge. The compressed fuel will be directed into one of the 35 cylinders 6 as soon as recess 19 comes into register with the port 16 and as soon as this fuel has been directed into cylinder 6 piston 18 will compress the fuel by moving towards the spark plug 9. Ignition of the 40 charge will then take place in the usual manner and the piston 18 will be driven away from the closed head of the cylinder so as to expose the exhaust port 20. Just prior to the opening of the port 16 the recess 45 19 will expose one of the nozzles 25 so that a jet of steam under pressure will be directed upward into the cylinder and toward the exhaust port, thereby scavenging the cylinder and eliminating carbon. The 50 steam can be supplied to the nozzles 25 from any source desired.

Importance is attached to the fact that the cylinders 6 are eccentrically disposed relative to the cylindrical portions of the 55 casing 1 because it is thus possible to reduce the number of connections between the pistons and the crank shaft. Furthermore by utilizing the guide portions 7 the engine can be made shorter and more compact than 60 heretofore and as the pistons are thereby kept out of contact with each other the friction is materially reduced and the engine rendered more efficient in operation.

What is claimed is:—

1. In an internal combustion engine the

combination with a casing having cylindrical portions, of spaced cylinders integral with the casing and having guide portions constituting extensions thereof and eccentrically mounted within the cylindrical portions of the casing, charging pistons mounted for reciprocation between said guide portions and the walls of the cylindrical portions of the casing, a firing piston mounted for reciprocation within each cylinder and its extension, a port for directing fuel from the path of each charging cylinder into the path of each firing cylinder, a fuel supply port adapted to be opened and closed by each of the charging pistons, an exhaust port in each cylinder, said firing pistons constituting means for opening and closing the exhaust and intake ports and those ports feeding fuel into the cylinders.

2. In an internal combustion engine a casing having cylindrical portions, cylinders extending from the casing, guide extensions upon the cylinders and eccentrically disposed within the respective cylindrical portions of the casing, a firing piston mounted for reciprocation in each cylinder and its guide extension, and a charging piston mounted for reciprocation between each guide extension and the wall of the cylindrical portion of the casing, a crank shaft, and connections between the crank shaft and the charging and firing pistons for operating each charging piston in a direction opposite to its firing piston.

3. In an internal combustion engine the combination with a casing having cylindrical portions, of cylinders, a guide extension upon each cylinder eccentrically mounted within one of the cylindrical portions of the casing, a firing piston mounted for reciprocation within each cylinder and its extension, a charging piston mounted for reciprocation between each guide extension and the cylindrical portion of the casing in which it is located, means for moving each firing piston and its charging piston in opposite directions respectively, each charging piston cooperating with its casing for compressing fuel in the path thereof, a port for conducting fuel from the path of each charging piston to one of the cylinders, an exhaust port communicating with each cylinder, a scavenging port opening into each cylinder, each firing piston constituting means for controlling the opening and closing of the ports in properly timed relation.

4. In an internal combustion engine a casing having a cylindrical portion, a charging piston mounted for reciprocation therein and having an eccentric opening therethrough, a cylinder, a guide extension thereon projecting through the opening in the charging piston, a firing piston mounted for reciprocation within the cylinder and its extension, and a port for conducting fuel from the path

of the charging piston to the path of the firing piston.

5. In an internal combustion engine a casing comprising cylindrical portions, a crank shaft, charging pistons mounted for reciprocation within the respective cylindrical portions and each having an eccentrically arranged opening therein, there being a recess within the active face of each piston, pitman connections between the crank shaft and the charging pistons, each connection being located where the distance is greatest between the periphery of the piston and the opening therein.

15 6. In an internal combustion engine the

combination with a casing having cylindrical portions, of charging pistons mounted for reciprocation within said portions, a tubular guide arranged eccentrically within each charging piston, a firing piston mounted for reciprocation within each guide, cylinders constituting continuations of the guides. 20

In testimony that we claim the foregoing as our own, we have hereto affixed our signatures in the presence of two witnesses.
